UNITED STATES PATENT OFFICE.

WILTON S. SCHUYLER, OF SPRINGFIELD, OHIO.

WASHING MACHINE.

Application filed September 24, 1923. Serial No. 664,637.

To all whom it may concern:

Be it known that I, WILTON S. SCHUYLER, a citizen of the United States, residing at Springfield, in the county of Clark and 5 State of Ohio, have invented certain new and useful Improvements in Washing Machines, of which the following is a specification.

This invention relates to washing machines, it more particularly relating to 10 means for partly counter-balancing the agitating device of such machines.

The object of my invention is to provide 15 a simple and effective mechanism for partly counter-balancing the agitating device of a washing machine whether it be an oscillatory cylinder, an oscillatory dolly, an oscillatory semi-cylindrical scrubber or other form of agitating device so that the device may 20 be readily removed from the tub or casing in which it operates.

A further and more specific object of the invention is to provide a mechanism of the character referred to consisting of a spring 25 member or members arranged to be placed under increasing tension as the agitating device is lowered into the tub so that in removing the device from the tub the springs will act to assist in raising the same.

30 In the accompanying drawings:

Fig. 1 is a top plan view of a washing machine of the oscillatory cylinder type with the cover removed showing my improved mechanism applied thereto.

35 Fig. 2 is a vertical section of the machine with the cover shown in position thereon, the section being on the line 2-2 of Fig. 1.

Fig. 3 is a top plan partly in section on 40 an enlarged scale of a portion of the machine and counter-balancing devices.

Fig. 4 is a side view of one of the supporting arms for the agitating member with the shafts in section.

Fig. 5 is a section on the line 5-5 of 45 Fig. 3.

In the drawings the improvements have been shown applied to a washing machine of the oscillatory cylinder type.

The tub proper is indicated at 1, being 50 preferably formed of sheet metal which is supported upon the frame 2. The top of the tub is enclosed in the usual way by a lid 3 and there is mounted in the tub a cylinder 4 which has means (not shown) for oscillating the same. The shaft 5 of the cylinder is mounted in open-top bearings 6 se-

cured to the casing so as to permit the cylinder to be removed from the tub when desired. A rock shaft 7 extends transversely across one end of the tub near the upper portion thereof, this rock shaft being mounted in bearings 8 which are secured in the ends of a tube 9 which is stationarily supported by the tub. To support the tube there is provided a pair of U-shaped clamps 10, the 60 free ends of which project through the casing 1 and a reinforcing plate 11 and are threaded to receive nuts 12 so that the tube may firmly clamp against spacing blocks 13 which are placed between the tube and the 65 inner wall of the casing.

A pair of arms 14 are secured to the rock shaft 7 by set screws 15 and the free ends of these arms are secured to lugs 16 projecting from sleeves 17 loosely mounted upon the cylinder shaft 5 at each end of the cylinder. One end of the shaft 7 projects through the casing 1 and is provided with a crank handle 18, a detent in the nature of a pin 19 arranged to engage either one of 80 a pair of recessed members 20 secured to the tub 1 so as to hold the cylinder in either raised or lowered position; a spring 21 being preferably employed to press the pin to engaging position. But one of these recessed members is shown in the present case, the other member 20 being in all respects like the one shown and located at the other limit of movement of the crank handle 18. To partly counter-balance the 85 weight of the cylinder 4 there are employed a pair of coil springs 22, one at each end of the rock shaft 7. The inner end of each of these springs is inserted in an aperture in the lug 23 projecting from the bearing 8 90 while the other end of the spring is bent and projects beneath its corresponding arm 14 as 95 clearly shown in Fig. 3.

As a result of this construction, when the cylinder is lowered into the casing, these 100 springs are placed under increasing tension, the maximum tension being such as to nearly but not quite counterbalance the weight of the cylinder when the cylinder is in its lowermost position. To raise the cylinder 105 the detent 19 is released and the crank employed to rotate the shaft 7 so as to raise the arms 14 and with them the cylinder, the springs assisting in this raising movement. In installing the springs, they are preferably 110 given an initial tension; that is, when the operating member is at the limit of its raised

position the spring will still be under some tension so as to insure the effective cooperation of the springs during the entire raising movement of the operating member.

5 Having thus described my invention, I claim:

1. In a washing machine, a tub, an agitating member hinged to the inner face of a wall of said tub so as to be swung into and out of said tub, and a pair of coil springs located inside of said tub, one at each end of said agitating member, and arranged to partly counterbalance the weight of said member.
- 10 2. In a washing machine, a tub, a rock shaft supported from the inner face of one of the walls of said tub, a pair of arms projecting from said rock shaft, an agitating member carried by the free ends of said arms, and a pair of coil springs about said rock shaft, one end of each spring being secured to a stationary part and the other end thereof bearing upon one of said arms.
- 15 3. In a washing machine, a tub, a rock shaft supported from the inner face of one of the walls of said tub, arms connected to said rock shaft, an agitating member supported by the free ends of said arms, a pair of coil springs about said rock shaft and
- 20 40 cooperating with said arms to partly counterbalance the weight of said agitating member, said rock shaft being extended through a wall of said tub, and a crank arm on the outer end of the extended part of said shaft for raising and lowering said agitating member.
- 25 45 5. In a washing machine, a tub, a rock shaft supported from the inner face of one of the walls of said tub, arms connected to said rock shaft, an agitating member sup-

ported by the free ends of said arms, a pair of coil springs about said rock shaft and cooperating with said arms to partly counterbalance the weight of said agitating member, said rock shaft being extended through a wall of said tub, and a crank arm on the outer end of the extended part of said shaft for raising and lowering said agitating member, and a detent carried by said crank arm to hold the same in different positions of adjustment.

55 6. In a washing machine, a tub, an oscillatory member, a rock shaft supported by said tub having one end projected through said tub and provided with a crank arm, arms connecting said rock shaft with said member, a pair of coil springs about said rock shaft, one end of each spring having a connection with its corresponding arm and the other end of said spring being connected to a stationary point, whereby when said member is lowered into said tub said springs will be placed under increasing tension.

60 7. In a washing machine, a tub, an oscillatory member, a tubular member connected with said tub having a bearing at each end thereof, a rock shaft journaled in said bearings, arms connected with said rock shaft and also with said oscillatory member, and a pair of coil springs at each end of said tubular member, one end of each spring having a connection with its corresponding arm and the other end thereof being connected with the corresponding bearing, whereby when said oscillatory member is lowered said springs will be placed under increasing tension.

In testimony whereof, I have hereunto set my hand this 21st day of September, 1923.

WILTON S. SCHUYLER.
